UNITED STATES PATENT OFFICE.

ADOLPH G. KAUFMAN, OF NEW YORK, N. Y.

HYDROCARBON-LAMP SUPPORT.

1,142,815.

Specification of Letters Patent. Patented June 15, 1915.

Application filed June 10, 1914. Serial No. 844,217.

To all whom it may concern:

Be it known that I, ADOLPH G. KAUFMAN, a citizen of the United States, residing at New York, in the county and State of New 5 York, have invented a new and useful Hydrocarbon-Lamp Support, of which the following is a specification.

This invention relates to hydrocarbon lamps, and especially to the class of lamps 10 where the hydrocarbon is converted into a gas before being burned; and the object of my invention is to provide a lamp so constructed that it may be removed from the normal support used when in use, and set 15 on a table, or floor when refilling.

The invention is designed as a companion application to the application for patent on a self-contained hydrocarbon lamp, filed June 10, 1914, Serial Number 844,218.

20 In the companion application a lamp is described in which the reservoir, bracket, generator, and burner, or burners are combined as an article of manufacture. With such a lamp it is desirable to take the same 25 from its support when filling, or cleaning, and rest it upon the floor, or a table. During such operation it is most desirable that the lamp should be supported in a firm manner. As, however, the lamp proper is necessarily located at some distance from the reservoir it is a difficult matter to support the 30 complete device. To overcome this difficulty I have so constructed the parts that the bracket itself will form one of the legs on 35 which the entire device may be supported; and I have formed coöperating supports in conjunction with the regular suspending rod of the reservoir to hold both the lamp and reservoir in an upright position when 40 resting on a table or floor.

The invention is illustrated in the accompanying drawing, in which—

Figure 1, is a side elevation of a hydrocarbon lamp constructed in accordance with 45 my invention; and Fig. 2, is an elevation, taken at right angles to Fig. 1.

In the drawing similar numerals of reference refer to the same parts in each of the views.

50 In practice, I provide a hydrocarbon lamp

having a suspending tube, or rod 4, reservoir 5, through which said suspending tube, or rod passes, a bracket 6, and lamp 7, with a support consisting of two legs, or feet 8, and 9, connected with the bottom of said suspending 55 tube, or rod outside the reservoir 7, as shown particularly in Fig. 2, and mounting on the ends thereof respectively the knobs 10, and 11, and in providing the bracket 6, with a knob 12, on a line with the knobs 10, and 60 11, whereby when the lamp is resting on a support, indicated by the line 13, the lamp will stand substantially level for the purpose of filling the reservoir through the part 14, or for the purpose of cleaning the 65 lamp. As the entire device is supported at three points located in a substantially horizontal plane; and two of these supports are connected directly with the suspending tube, or rod passing through the reservoir, and 70 these three points are so located that both the lamp proper and reservoir will be firmly supported, it is evident that I have provided simple and efficient means to perform the desired act of holding the entire device 75 in a perfectly firm manner.

While I have shown but one lamp connected with the reservoir 5, it is evident that a lamp could be mounted on each side of the reservoir in substantially the same manner 80 as the lamp shown is mounted on one side thereof.

It will thus be seen that I have provided simple and efficient means for supporting a hydrocarbon lamp of the character described 85 in a firm manner when removed from the normal support and resting on a floor, or table; and I have provided such a support without detracting from the appearance of the device. By utilizing a part of the lamp 90 bracket to form one support I am not only able to provide a very firm device; but by such a construction I am able to make a hydrocarbon lamp in which the real purpose of the particular positioning of the bracket 95 with the contact point thereon will not be apparent when the lamp is performing its normal function; and, consequently, the attractive appearance of the lamp will not be marred.

I claim:
A hydrocarbon lamp having a reservoir, a suspending device passing through said reservoir, a bracket, and a lamp proper, a support comprising two legs each having one end secured to said suspending device and a knob mounted on the other end, and said bracket having a knob, the knobs on

said legs and bracket being in the same horizontal plane, for the purpose set forth. 10

Dated 9th June, 1914.

ADOLPH G. KAUFMAN.
